UNITED STATES PATENT OFFICE.

JULES BUCHEL, OF NEW ORLEANS, LOUISIANA.

AMMONIA ABSORPTION REFRIGERATION METHOD AND APPARATUS.

Application filed October 10, 1921. Serial No. 506,710.

To all whom it may concern:

Be it known that I, JULES BUCHEL, a citizen of the United States, and resident of New Orleans, in the parish of Orleans and State of Louisiana, have invented certain new and useful Improvements in Ammonia Absorption Refrigeration Methods and Apparatus, of which the following is a specification.

10 My invention resides in an ammonia absorption refrigerating system in which the ammonia gas is continuously boiled off, reabsorbed, and returned to the generator without the use of force pumps or other mechanical means.

My invention provides a refrigerating system which only requires the application of heat and cooling water from any convenient source, the refrigeration once initiated being maintained continuously, and includes a number of specific features of construction and operation which will become clear from the following description taken in conjunction with the accompanying drawings forming part of this specification and in which:—

Figure 1 is a diagrammatic view of my improved refrigerating system;

Figure 2 is a fragmentary vertical central sectional view taken through the left hand regenerator and its connected valves;

Figure 3 is a fragmentary central sectional view of the generator showing the arrangement of the evaporating pans therein;

Figure 4 is a vertical central sectional view of the expansion valve;

Figures 5 and 6 are horizontal sectional views on the lines 5—5 and 6—6, respectively, of Figure 3; and

Figure 7 is a plan view of a valve part shown in Figure 2.

Drawing a vertical line through the axis of the generator as the center of the system, the right and left sides are duplicates of each other except for the condensing coil 5, the expansion valve 6, and the refrigerating coil 7.

Similar parts of the two sides are designated with the same numeral using the index "a" for the right side and the index 50 "b" for the left side.

Figure 1. A generator 1, filled with aqua ammonia to line 54, kept continuously boiling by a source of heat 2, controlled by a valve 3, accumulates a pressure which is indicated by gauge 8 on dome 4. The ammonia gas flows through pipe 9 into the double pipe condenser 5, reaches valve 6 in a liquid state, forces this valve open, flows into refrigerating coil 7, vaporizes therein, passes out through pipe 10, fills pipes 31^a and 31^b, flows alternately into regenerators 11^a and 11^b through check valves 21^a and 21^b.

Ammonia gas also flows alternately and intermittently from dome 4 through pipes 17^a and 17^b, valves 13^a and 13^b, pipes 18^a and 18^b to opposite sides through 12^a and 12^b into the tops of regenerators 11^a and 11^b.

Hot weak liquor flows alternately and intermittently from generator 1 through pipes 28^a and 28^b. If initiated through 28^a it flows to the top of heating coil 27^a inside of regenerator 11^a, down through said coil, emerges via 26^a, enters coil 25^a of the intercooler 24^a, flowing down and out through 29^a, then up and through filtering chamber 86^a, control valve 16^a and connection 12^a, into the top of regenerator 11^b to meet and absorb ammonia gas entering via 21^b. The regenerator 11^a is at this time full of ammonia gas under generator pressure.

Cooling water is supplied through valve 32, pipe 33, annular space 34 in the double pipe condenser 5, pipe 35, to alternately acting water control valves 15^a and 15^b. If the flow is initiated through valve 15^a it will be conveyed through pipe 19^a to the top of the cooling coil 30^a, down through said coil, emerges via pipe 36^a, crosses to the right, enters the bottom of intercooler shell 24^a, flows upward therein, goes to waste through 37^a, carrying with it heat abstracted from condensation in 5, absorption in 11^b, and hot liquor flowing through coil 25^a.

When regenerator 11^a is under generator pressure valve 13^a is closed and admits no ammonia gas and pressure via pipe 18^a to the top of 11^b, water control valve 15^a is wide open and supplying water via pipe 19^a to cooling coil 30^b in regenerator 11^b to abstract the heat of absorption, check valve 100

21^a is closed, liquor control valve 16^a is wide open but admits no liquor to 11^a because of the balanced pressure and the hydrostatic head between 12^a and the liquor level 54 being low.

At this time regenerator 11^b is under a low pressure and absorbing ammonia gas flowing in through check valve 21^b; valve 18^b is open and admitting ammonia gas via pipe 18^b to the top of 11^a, water control valve 15^b is closed and does not admit any water via pipe 19^b to cooling coil 30^a in 11^a, liquor control valve 16^b is admitting cold weak liquor to 11^b in direct proportion to the amount of ammonia gas to be absorbed and maintains a constant pressure and temperature in the refrigerating coil 7.

Whenever valve 16^b admits cold weak liquor to regenerator 11^b an equal amount of hot weak liquor flows from 28^a down through heating coil 27^a in regenerator 11^a and prevents condensation of ammonia gas therein. However, when 11^a is full of strong liquor the heating coil 27^a generally supplies enough heat to cause the top surface of the contained liquor to boil, exceed the generator pressure, and force the contents out via check valve 23^a and nozzle 41^a into the upper pan 37 inside of the generator 1. This excess pressure also forces some ammonia gas via pipe 18^b through the open equalizing valve 13^b and pipe 17^b into dome 4. However, when the system is operating much below its full capacity the coil 27^a does not supply enough heat, owing to radiation and conduction losses, to bring the top surface of the strong liquor in 11^a to its boiling temperature under generator pressure and there is then a reverse flow of ammonia gas from dome 4, via the open valve 13^b and pipe 18^b into 11^a, causing the liquor to flow back into the generator by gravity through check valve 23^a.

Generator 1 is provided with a vertical series of pans 37, 46 and 52 to receive the strong liquor from nozzles 41^a and 41^b which flows down through the generator step by step. Every other pan in the series has a central opening 38 and at the outer edges of the alternate pans annular openings 47, so that the liquor flows down in a zigzag path and the ammonia gas upward in the same manner.

Both regenerators consist of a shell 11, heating coil 27, cooling coil 30, standpipe 20 with horizontal branches such as 22 connecting with check valves 21 and 23. Across the top, a double T fitting with branches 12, 14 and 71 has tubular openings 55, 56 and 57, connecting the interior of regenerators 11 with the under side of diaphragms 60, 93 and 72, respectively of the control valves 13, 15 and 16.

Check valves 21 and 23 are both alike and

embody a special feature in being provided with valves made of thin sheet metal 108 resting on tubular seats 107 and their vertical movement limited by stops 109.

The water control valves 15 are composed of two flanged members 90 and 91 with a steel diaphragm 93 clamped between them by bolts 92. 91 is capped by a member 101 having a central opening connecting with pipe 35 and radial openings 102 leading to valve 99 which is seated on a tubular member 98. Inside of 98 there is a thrust member 97 with guide pins 100 and the lower flanged end of 97 is pressed against diaphragm 93 by a spring 94 of sufficient strength to hold the diaphragm 93 down and the thrust member 97 away from valve 99 against any pressure up to 100 pounds per square inch in regenerator 11 and therefore during the absorption period these valves are always closed as the absorption pressure is never over 25 pounds and no water will flow from 35 through pipe 19 to the opposite regenerator.

The liquor control valves 16 are composed of two flanged members 73 and 74 with a steel diaphragm 72 clamped between them by bolts 75. A threaded member 82 screws into 74 to compress spring 81 transmitting pressure to flanged member 83 centrally guided by a cone 85 attached to diaphragm 72. Below 72 there is a flanged valve member 77 pressed against the diaphragm by a spring 78 which is only strong enough to keep 77 in contact with 72 as the latter moves up and down. When the pressure in regenerator 11 is less than that due to spring tension 81, the valve 77 is forced against seat 80 and prevents any flow of liquor from pipe 29 through cotton wool in filtering chamber 86, tubular member 79, openings 57 and 55 into regenerator 11. The adjustment of screw 82 determines the absorption pressure in regenerator 11 and the temperature in refrigerating coil 7.

The equalizing valves 13 are composed of two flanged members 58 and 59 with a steel diaphragm 60 clamped between them by bolts 61. Back of the diaphragm 60 there is a spring 66 adjusted to a pressure of 10 pounds in valve 13^a and 12 pounds in valve 13^b. On the opposite side there is a flanged valve member 68 pressed against diaphragm 60 by a spring 65 which is only strong enough to hold 68 in contact with 60 as the latter moves to and fro. With equal pressures on both sides of diaphragm 60, spring 66 will force valve 68 against seat 69 and prevent any flow of ammonia gas from pipe 17 through pipe 18 to the opposite regenerator.

When regenerator 11^b is under a low pressure and absorbing, generator pressure through pipe 17 acting on diaphragm 60 will

overcome spring tension 66 and force valve 68 from its seat and admit ammonia gas to the opposite regenerator via pipe 18^b. Whenever the pressure in regenerator 11^b is 5 only 12 pounds less than that in generator 1, valve 68^b begins to close. In regenerator 11^a, a difference of less than 10 pounds causes valve 68^a to close. The two-pound difference in tension between springs 66^a and 10 66^b is without effect on the operating functions of the respective equalizing valves, but the apparatus is not self starting if there is no such difference.

Figure 4. Automatic expansion valve 6 is 15 composed of two flanged members 111 and 112, with a steel diaphragm 110 clamped between them by bolts 133. A threaded member 113 screws into 112 to compress spring 114 transmitting pressure to flanged member 115 centrally guided by a cone 119 attached to diaphragm 110. Below diaphragm 110 and within counterbore 126, there is a flanged valve member 127 pressed against the diaphragm by a spring 128 20 which is only strong enough to hold 127 in contact with 110 as the latter moves to and fro. Valve 127 is seated on the end of a tubular member 120 and controls the flow of liquefied ammonia gas through seat and orifice 125. Liquefied ammonia from condenser 5, flows through cotton wool 131, in 25 annular space between 111 and 120, is filtered, flows into counterbore 126 through orifices 130 in screw cap 124, overcomes the tension of spring 114, forces valve 127 off its seat 125, flows down through 120, into 30 refrigerating coil 7. The maximum generator pressure is determined by the adjustment of screw 113 and conditioned by the 35 temperature of the water supply.

The filtering chambers 86^a and 86^b, filled with cotton wool, are provided to filter the weak liquor as it flows into the regenerators to continuously remove small particles of 40 any adventitious matter that might interfere with proper valve action.

Starting with a cold system, properly charged, under a moderate vacuum, we find 45 all the control valves closed. We light burner 2, and presently the pressure in generator 1 rises until it is 10 pounds per square inch and begins to overcome the spring resistance 66^a in valve 13^a, forcing valve 68^a off its seat and admitting ammonia gas to 50 regenerator 11^b through pipes 17^a and 18^a.

From this moment on, the pressure in regenerator 11^b rises and keeps pace with the generator pressure up to the maximum for 55 which the expansion valve 6 is adjusted, but this pressure in regenerator 11^b immediately reacts against the diaphragm 60^b of the valve 13^b, reinforcing the spring tension 66^b, holds the valve 68^b closed, and prevents ammonia gas from flowing through pipes 17^b.

and 18^b into regenerator 11^a and consequently the latter retains its vacuum and is ready to receive ammonia gas from the refrigerating coil 7.

With valves 13 equally tensioned however, there would have been a simultaneous flow 70 of ammonia gas into both regenerators, keeping pace with the generator pressure, making it impossible to initiate absorption, and rendering the system inoperative.

The pressure in the system continues to 75 rise until it equals 100 pounds per square inch, opens control valve 15^b, admits a flow of cold water from pipe 35 via pipe 19^b through coil 30^a, in regenerator 11^a, crosses over via pipe 36^a to intercooler 24^b and 80 flows to waste from 37^b. The system is thus prepared for absorption in 11^a and for cooling hot weak liquor in coil 25^b.

The pressure continues to rise until it 85 equals 200 pounds per square inch and forces open the expansion valve 6, initiates refrigeration in coil 7, the ammonia gas flowing through check valve 21^a into regenerator 11^a.

Presently the rise of pressure in regenerator 11^a overcomes the spring tension in valve 90 16^a admitting a flow of cold weak liquor to absorb the ammonia gas, this liquor having lost its heat while flowing through coils 27^b and 25^b. Absorption is now in progress, its pressure under control of valve 16^a, and 95 admitting only enough liquor at any instant to completely absorb the ammonia gas.

Finally, the regenerator 11^a is full of saturated ammonia liquor, a further rise in pressure throws valve 16^a wide open, check valve 100 21^a closes, hydrostatic pressure accumulates until it equals the generator pressure, equalizing valve 13^a is closed, control valve 15^a is forced open, cold water flows via pipe 19^a through coil 30^b causing a pressure drop in 105 11^b, a rush of weak liquor through the now wide open valve 16^b, a rapid absorption of the contained ammonia gas, and as the pressure finally falls below that of the adjustment of 16^b this valve closes until ammonia 110 gas flowing from refrigerating coil 7 opens it again. In the meantime, as soon as the pressure in regenerator 11^b has dropped to 12 pounds less than the pressure in generator 1, valve 13^b opens and admits ammonia 115 gas to the top of the now full regenerator 11^a. In the meantime also, the rush of liquor into 11^b has brought heating coil 27^a into action, heated the top surface of the liquor in 11^a to its boiling point and forced 120 its contents back into the generator via check valve 23^a and nozzle 41^a.

Absorption is now proceeding in regenerator 11^b and as liquor continues to flow 125 through coil 27^a it keeps the regenerator 11^a hot enough to prevent any condensation of ammonia gas therein until it is ready to reverse and absorb again.

As the weak liquor flowing from the generator down through the heating coil 27 is usually at a temperature of 350° Fahr., and the boiling point, under generator pressure, of the strong liquor is not usually over 250° Fahr., and often much less, the temperature difference and quantity of heat is sufficient to boil the upper surface of the said liquor, but is quite insufficient to do so if the direction 10 of the flow is reversed, as in the latter case the heat is diffused over the whole liquor-volume and the action of the apparatus becomes not only uneconomical but erratic and unreliable as well.

15 The cycles run on consecutively, reversing every few minutes, as long as the heat is applied and the cooling water is flowing. The reversals of cycle are effected so quickly that there is only a slight rise of pressure 20 in the refrigerating coil during the period of transition and therefore no interference with the evaporation of the liquefied ammonia or the continuous production of refrigeration.

25 Should the supply of heat be increased the quantity of ammonia passing through expansion valve 6 also increases, pressure in regenerator rises, more liquor is admitted, the cycles are accelerated, and a correspondingly greater amount of refrigeration is produced. The capacity may thus be varied 30 from zero to the maximum by simply varying the heat supply and without disturbing any of the other adjustments.

35 The regenerators are so named because they restore to the liquor its original state of saturation, temperature and pressure.

As many modifications of my invention will readily suggest themselves to one 40 skilled in the art, I do not limit or confine my invention to the specific steps or the exact construction herein shown and described.

I claim:

1. The herein described method of continuous ammonia absorption refrigeration 45 which consists in continuously applying heat to a nucleus of ammonia liquor in a gradient of concentration, continuously evaporating ammonia gas from said nucleus under sufficient pressure to subsequently effect its liquefaction at a lower temperature, producing continuous refrigeration by subsequent vaporization of the liquefied ammonia under a diminished pressure, extracting hot 50 weak liquor from said nucleus, cooling the extracted liquor causing it to absorb the said vaporized ammonia, and when said extracted liquor has become saturated applying heat thereto to subject it to pressure and cause it to be returned to the said nucleus.

2. The herein described method of continuous ammonia absorption refrigeration which consists in continuously applying heat 60 to a nucleus of ammonia liquor in a gra-

dient of concentration, continuously evaporating ammonia gas from said nucleus under sufficient pressure to subsequently effect its liquefaction at a lower temperature, producing continuous refrigeration by subsequent vaporization of the liquefied ammonia under a diminished pressure, extracting hot 65 weak liquor from said nucleus, cooling the extracted liquor causing it to absorb the said vaporized ammonia, and when said extracted liquor has become saturated applying heat thereto derived from the said nucleus, to subject the extracted liquor to pressure and cause it to be returned to the said nucleus.

3. The herein described method of continuous ammonia absorption refrigeration 80 which consists in continuously applying heat to a nucleus of ammonia liquor in a gradient of concentration, continuously evaporating ammonia gas from said nucleus under sufficient pressure to subsequently effect its liquefaction at a lower temperature, producing continuous refrigeration by subsequent vaporization of the liquefied ammonia under a diminished pressure, extracting hot 85 weak liquor from said nucleus, cooling the extracted liquor causing it to absorb the said vaporized ammonia, and when said extracted liquor has become saturated extracting a successive quantity of hot weak liquor from the 90 said nucleus, transferring heat from the said second quantity to the first quantity to subject the first quantity to pressure and cause it to be returned to the said nucleus.

4. The herein described method of continuous ammonia absorption refrigeration 100 which consists in continuously applying heat to a nucleus of ammonia liquor in a gradient of concentration, continuously evaporating ammonia gas from said nucleus under sufficient pressure to subsequently effect 105 its liquefaction at a lower temperature, producing continuous refrigeration by subsequent vaporization of the liquefied ammonia under a diminished pressure, extracting successive quantities of hot weak liquor from 110 said nucleus, successively cooling said extracted quantities, causing them to successively absorb the said vaporized ammonia, and when said extracted quantities have become saturated causing them to be heated 115 and their upper surfaces partly vaporized by the next successive extracted quantity and thereby generating enough pressure to cause their return to the said nucleus.

5. In a closed circulatory ammonia absorption refrigeration system, a single generator, means for continuously applying heat thereto, means for maintaining the ammonia liquor in the generator in a gradient of strength with the weaker liquor at the bottom, two regenerators adapted to alternately receive weak liquor from the generator and to alternately absorb ammonia gas.

received from the refrigerating coil, and means for automatically and successively returning the contents of the regenerators back into the generator while heat is being applied thereto.

6. In a closed circulatory ammonia absorption refrigeration system, a generator, two regenerators, automatic means for successively and alternately delivering hot and cold weak liquor and ammonia gas to the regenerators, means for maintaining generator pressure in one of the regenerators and absorption pressure in the other, water control and equalizing valves for said regenerators, means for accumulating pressure in the regenerators upon termination of absorption and thereby positively actuating the water control and equalizing valves governing the opposite regenerator to effect a reversal of cycle, as and for the purpose specified.

Signed at New Orleans, La., this first day of October, 1921.

JULES BUCHEL.
